UNITED STATES PATENT OFFICE.

PAUL E. MONSON, OF BERKELEY, CALIFORNIA, ASSIGNOR TO BRYSON D. HORTON, OF DETROIT, MICHIGAN.

CABINET FOR ELECTRIC SWITCHES.

Application filed July 15, 1918. Serial No. 245,114.

To all whom it may concern:

Be it known that I, PAUL E. MONSON, a citizen of the United States, residing at Berkeley, in the county of Alameda and State of California, have invented certain new and useful Improvements in Cabinets for Electric Switches, of which the following is a specification.

This invention relates to improvements in cabinets for electric switches of the knife type. Among the objects which I accomplish by the use of my improved cabinet is to so arrange the cabinet and switch that under ordinary operating conditions the latter cannot be closed while the cabinet is open, or the cabinet be opened while the switch is closed. In other words, the cabinet and switch so interlock that it is necessary to open the switch in order to gain access to the interior of the cabinet and when once the cabinet is opened the switch cannot be closed until the cabinet is closed and locked. Furthermore, the device is so arranged that the switch can be locked in its open position when the box is closed.

A further object is to so construct the door or cover of the cabinet that it may be hinged either on one of the side walls or one of the end walls and that when it is open it swings entirely clear of the cabinet allowing plenty of room for locking in the conduits, renewing fuses or testing the wiring.

With these and other objects in view as will hereinafter appear in the specification it will be seen that my invention consists of certain novel features of construction, combinations and arrangements of parts herein described and more specifically pointed out in the appended claims.

Reference being had to the drawings forming a part of this specification,

Figure 1 is a view in front elevation of my improved switch cabinet with the door open disclosing the arrangement of the switch and operating mechanism.

Figure 2 is a view in section through the cabinet showing the switch and locking mechanism positioned as when the cover is closed.

Figure 3 is a sectional view through the door of the cabinet and the locking mechanism.

Figure 4 is a sectional view through the locking mechanism on a plane at right angles to Figure 3.

Figure 5 is a view similar to Figure 3 showing a modified form of locking mechanism.

Figure 6 is a view in transverse section of the modified locking mechanism.

Figure 7 is a view similar to Figure 3 showing a modification for double-throw switches.

Figure 8 is a perspective view of a key-like member used to disable the interlocking mechanism.

Referring to corresponding parts of the several views by the same numerals of reference 1 denotes a rectangular casing or box having the cover 2. This cover as here illustrated, is hinged to one of the side walls as at 13 and is constructed with the flange 14 around its entire periphery. This flange is adapted to extend partly down on the walls of the cabinet to prevent any possibility of hot sparks flying out of the cabinet through the crack around the cover. On the outside of the cover is attached an eye 19 or other suitable means by which the same may be handled and on the inside is attached an eye 16 the opening 17 therein being engaged by the locking mechanism when the cover is closed.

The cabinet comprises the base 3, the end walls 4 and 5 and the side walls 6 and 7. Attached to the bottom 3 is the base 8 of an ordinary knife switch, the blades 9 of which are connected by the insulating yoke 10. I have here illustrated the cabinet as being provided with openings in the end walls 4 and 5 through which extend the wiring conduits 11, which conduits are held in place by means of the locking nuts 12.

The lock mechanism denoted generally by 18 is riveted to the inside of one of the side walls and comprises a casing 20 wherein is pivotally mounted an oscillative plate 21. This member is provided with the arcuate hook 22 of such shape and size that when the cover is closed and this member is rotated, the hook will enter the opening 17 of eye 16, the casing 20 being provided with an opening 23 in the front thereof through which the eye may pass.

The width of plate 21 is less than that of the eye 16 and oscillatively mounted alongside of this plate is a bell-crank lever 25 having an arm 26 which lies alongside of member 21 and at certain times is positioned over the opening 23. This is urged

toward opening 23 by means of a spring 27 and is adapted to be depressed by the eye 16. The other arm 30 of the bell-crank extends at an angle with arm 26, is bent laterally into alignment with plate 21 and is provided with the forwardly extending finger 31.

Member 21, on the edge toward the bell-crank, is arc-shaped and is provided with a notch 32 of such size that the finger 31 fits snugly within, under certain conditions of operation. On the side of plate 21 opposite notch 32 is provided an arm 29 which extends below the casing 20 forming a recess 34 for the reception of the cross-bar 28 of the locking lever 35.

This lever within the casing, is U-shaped having the portion 28 extending across the casing and having the ends pivotally mounted in the side walls thereof as shown at 36 and 37. The end which extends through the side walls at 37 is then bent parallel to the side wall and on the end is provided with an eye 38 that forms a grip for operating the lever and also for locking the same, under certain conditions. The locking lever is preferably pivoted in the side walls on an axis in alignment with the axes of the knife blades 9 and the cross-bar 28 is connected to the switch yoke 10 by means of a slotted member 40.

In use when the lid is closed, the eye 16 depresses arm 26 of the bell-crank 25 and withdraws the finger 31 from slot 32. This frees plate 21 so that by moving the locking lever 35 the cross-bar pushes the plate around as it moves toward the switch base, causing the hook 22 to engage the opening in eye 16. Thus the lid is effectively locked when the switch is closed.

To open the box it is necessary by means of the locking lever, to disengage the switch blades from the clips and rotate the cross-bar until it enters recess 34 and then to move it a further distance until the hook is disengaged from the eye. Then when the lid is opened the finger 31 enters slot 32 and so prevents further movement of the plate. At this time the recess 34 is substantially in a vertical position so that the cross-bar 28 cannot be withdrawn therefrom in either direction. This effectively prevents any further movement of the switch so long as the cover is open.

In the form of my device as shown in Figures 1 to 4, inclusive, when the door is open the switch may be released from the locking mechanism and closed by inserting a small tool through the opening 23 and pressing down the arm 26 until the member 21 is free to rotate. The switch may then be closed with the cover open which is desirable for the purpose of testing contact between the switch blades and clips. That the switch may be released in the manner above de-

scribed is not a serious objection but is rather an advantage, but in order to absolutely prevent the switch from being closed while the door is open by anyone other than a person provided with a proper key, I provide a modified form of lock mechanism as shown in Figures 5, 6 and 8.

In this arrangement the switch and locking lever 35 are the same as that previously described, the difference being in the locking mechanism. The latter comprises a casing 50 wherein is pivotally mounted the lock plate 51 which is provided with arms 52 and 53 corresponding in function with the arms 22 and 29 of plate 21. Likewise, a recess 54 is formed corresponding to the recess 34 and which is likewise adapted to receive the cross bar 28 of the operating lever.

On each side of the member 51 is mounted a three arm lever 56 the forward arms 57 of which correspond in function to the arm 26 of the simpler form and which are normally adapted to be rotated by suitable means attached to the lid of the box. The arms 58 are arranged to cooperate with abutments 59 on the opposite surfaces of member 51 and a slot 60 is provided between the abutments to allow rotation of the plate when the levers are properly positioned.

It will be noted that the arms 58 are curved on an arc the center of which is in the axis of plate 51. The other arms 61 are provided for attaching springs 63, the opposite ends of which are attached to an arm 62 on the member 51. On the front of plate 51 is provided a stop 64 which contacts with the casing and prevents the disengagement of the cross-bar 28 from slot 54 in the wrong direction.

In this form of the device the eye 66 which projects into the lock casing is provided with lugs 71 which are spaced to correspond with the angle of the arms 57 so that when the door is closed these lugs press down on the arms 57 rotating the corresponding levers a sufficient distance that the arms 58 are positioned exactly opposite the slot 60 between the abutments 59.

I prefer to construct this eye as a continuation of plate 65 on the outside of the lid and which is securely riveted thereto. On the outside of plate 65 is an eye 19 which serves as a handle and for locking the switch open when the lid is closed.

With this form of box a key is provided having lugs positioned to correspond to lugs 71 and this key may be used to depress the arms 57 when the lid is open.

It will be noted that the device comprising the key has specially shaped portions which cooperate with complementary portions in the interlocking device. In other words, the gist of my invention in this respect resides in utilizing a device resembling a key

in form or function, that is, key-like, whereby an interlock may be disabled through the use of such a means only. For example, such a key may embody a peculiarly shaped socket portion adapted to cooperate with a complementary portion on one of the interlocking members. This prevents the interlock from being disabled by unauthorized persons who may try to disable the interlock with some sort of tool, because, as my invention contemplates complementary portions in the interlocking device and on an instrument which I have designated as key-like, it will not be possible for the ordinary workman to normally tamper with and disable the interlock, said unauthorized workman not, of course, having the particular key-like means which is designed for use with the switch in question. In selling interlock switches embodying my invention the manufacturer will sell in addition thereto the key-like device through the use of which the interlocking mechanism may be disabled. In this connection I wish it understood that when I refer to a key I mean an instrument having wards, or portions, shaped to fit one of the elements of the particular lock and operated by turning or pushing.

With this form of cabinet it is necessary to depress the levers 56 exactly the right amount before the switch can be operated. When the cover of the cabinet is open the ends of arms 58 rest against the abutments 59 so that the plate 51 cannot be rotated and therefore the operating lever moved to close the switch. But when the cover is closed the lugs 71 depress the lever arms 57 and rotate arms 58 the proper amount to position their ends opposite openings 60 and permit rotation of plate 51.

To adapt my device for double-throw switches I provide the revolvable plate 21' with two arcuate hooks 22' and 80 pointing in opposite directions and separated by a distance equal or greater than the thickness of eye 16. The lower edge of this plate is provided with a notch 83 formed by the edges 81 and 82, one of which allows the entrance of lock-bar 35 from one direction, and the other of which allows its entrance from the opposite direction when the plate is in its extreme opposite position.

In this form of my device when the lock-bar 35 moves in a clockwise direction, as the view in Figure 7, the cross-bar thereof contacts with the edge 81 and further movement causes plate 21' to be rotated. Now when the handle 38 is upright, or in its intermediate position, plate 21' has moved such an amount that the opening between the hooks 22' and 80 is in alinement with the eye 16 and the notch 83 is symmetrically disposed with respect to a vertical line through the pivotal axis of plate 21'.

The cover can then be opened which allows

finger 31 to enter slot 32 and so lock plate 21'. Now when held in this position, the edges 81 and 82 prevent movement of the bar 35 in either direction and hence the switch cannot be closed.

If it is desired to close the switch in the opposite side, then after the cover is closed bar 35 is further rotated in a clockwise direction and pushes aside the edge 81 which rotates plate 21' and causes hook 80 to engage the opening of eye 16. When this has taken place the plate has moved through a sufficient angle that the edge 81 releases the locking bar and the switch may be closed.

While I have described but two embodiments of my invention, it is apparent that many modifications therein may occur to those skilled in the art without departing from the spirit of this invention, and I desire, therefore, that the same be limited only by the prior art or by the scope of the appended claims.

I claim as new and wish to cover by Letters Patent:—

1. A switch device comprising in combination with an electrical switch, a cabinet, a hinged cover therefor, a U-shaped lever having its ends pivotally mounted in the side walls of said cabinet and having one end extending therethrough to form an operating handle, means operatively connecting said lever and said switch, a lock mechanism, an eye attached to said cover and adapted to be engaged by said lock mechanism, an arm extending from said lock mechanism into the path of said lever and operable thereby, and means for holding said lever in engagement with said lock mechanism when said eye is disengaged therefrom.

2. A device of the character described comprising a cabinet, a cover therefor, an electric switch in said cabinet, a lever for opening and closing said switch, an operating handle for said lever on the outside of said cabinet, a lock mechanism for said cover comprising a plate having a portion extending therefrom adapted to be moved when said lever is moved to open and close said switch, said plate having a recess adapted to engage said lever, an interlocking lever to hold said plate when said cover is open, and means carried by said cover for releasing said interlocking lever.

3. A device of the character described comprising a cabinet, a cover therefor, an electric switch within said cabinet, an operating lever for said switch movable from the outside of the cabinet, a lock mechanism attached to said cabinet, an eye on said cover adapted to be engaged by said lock, said lock comprising a pivotally mounted plate, an arm extending therefrom into the path of said lever, said plate having a recess adapted to embrace said lever, a hook

- on said plate adapted to engage said eye, and an interlocking lever to hold said plate when said eye is disengaged from said lock.
4. The combination with a switch cabinet, an electric switch therein, and a hinged cover therefor, an operating lever for opening and closing said switch, a lock mechanism for said cover operable by the movement of said lever, interlocking means embodied in said lock for holding said switch and lever in their open position when said cover is open, and means comprising a key-like member for disabling said lock whereby the switch can be closed while the cover is open, said last means having a portion adapted to cooperate with a complementary part of the interlocking means whereby said disablement may be normally effected through the use of said key-like means only.
5. The combination with a switch cabinet, an electric switch therein, and a hinged cover therefor, an operating lever for opening and closing said switch, a lock mechanism for said cover operable by the movement of said lever, said lock mechanism being protected by a casing whereby it is substantially inaccessible, interlocking means embodied in said lock for holding said switch and lever in their open position when said cover is open and for holding said cover closed when said switch is closed, and means comprising a key-like member insertable through said lock casing to engage and disable said interlock.
6. The combination with a switch cabinet, an electric switch therein, and a hinged cover therefor, an operating lever for opening and closing the switch, a lock mechanism for said cover operable by the movement of said lever, said lock mechanism being protected by a covering whereby it is substantially inaccessible, interlocking means having key engageable portions embodied in said lock mechanism, and means comprising a key-like member having portions fitted to register with said engageable portions on said interlocking means whereby the interlocking of the switch may be disabled.
7. In a double throw switch having a casing provided with a cover, an interlocking member whereby the switch cannot be closed in either direction while the cover is open and whereby the cover cannot be opened when the switch is in either of its "on" positions and means for disabling the interlocking mechanism.
8. In a double throw switch having a casing provided with a cover, an interlocking member, means for holding said member in position whereby the switch cannot be closed in either direction while the cover is open, means on the cover for releasing said first named means to allow operation of the switch to either of its "on" positions,
- means associated with said interlocking member whereby the cover cannot be opened when the switch is in either of its "on" positions and means comprising a key for disabling the interlocking mechanism.
9. In an enclosed switch, the combination of an interlocking cover and a switch mechanism whereby normally the cover can not be opened until the switch is opened and the switch can not be closed until the cover is closed, and key-like means for disabling the interlock so that said cover and said switch may be temporarily rendered independent, said key-like means being specially shaped to cooperate with a complementary part on the interlock whereby said disablement may be normally effected through the use of said key-like means only.
10. In an enclosed switch having a casing provided with a cover, interlocking means adapted to lock said switch while the cover is open, and key-like means for disabling said interlocking means, said key-like means having a portion adapted to cooperate with a complementary part of the interlocking means whereby said disablement may be normally effected through the use of said key-like means only.
11. In combination, a switch and a housing therefor, a movable cover for said housing, means lying within said housing adjacent to said cover for locking said cover in closed position while said switch is closed, said means embodied in a casing having an opening in the side facing said cover, and means for passing through said opening to disable said locking means, said means being specially formed and adapted to cooperate with the complementary means within said casing.
12. In combination, a switch and a housing therefor, a movable cover for said housing, means lying within said housing adjacent to said cover for locking said switch in open position while said cover is open, a casing for enclosing said means and rendering the same substantially inaccessible, and key disabling means having surfaces providing a set engagement with said locking means for releasing said switch.
13. In combination, a switch, a cabinet for said switch, a movable cover for said cabinet, lever means for operating said switch, an interlocking element between said cover and said lever means for locking said switch in a predetermined position while said cover is open, engageable elements cooperating with said interlocking element, and key disabling means having engageable elements adapted to engage first said engageable elements for releasing said switch.
14. In combination, a switch, a cabinet for said switch, a movable cover for said switch, lever means for operating said switch, an interlock for preventing the closing move-

ment of said switch while said cover is opened and for preventing the opening of said cover while said switch is closed, and key-like means having a plurality of engaging surfaces for disabling said interlock.

15. In combination, a switch, a cabinet for said switch, a movable cover for said cabinet, means for operating said switch, an

interlock between said switch and said cover, said interlock including a plurality of wards, and key means having shoulders for engaging said wards to disable said interlock.

In testimony whereof I affix my signature.

PAUL E. MONSON.
